DESIGN FOR A COVER FOR TOBACCO PIPES

Jacques Schwalbe, New York, N. Y.

Application July 19, 1941, Serial No. 102,291

Term of patent 3½ years

To all whom it may concern:

Be it known that I, Jacques Schwalbe, a citizen of Belgium and residing at the city, county, and State of New York, have invented a new, original, and ornamental Design for a Cover for Tobacco Pipes, of which the following is a specification, reference being had to the accompanying drawing, forming part thereof.

Figure 1 is a top plan view of the cover for tobacco pipes embodying my design as it appears when opened;

Fig. 2 is a side elevational view of the same;

Fig. 3 is a bottom plan view of the same;

Fig. 4 is a top plan view of the pipe cover embodying my design as it appears when closed;

Fig. 5 is a side elevational view of the closed pipe cover looking from the left of Fig. 4; and

Fig. 6 is a side elevation at right angles to Fig. 5.

I claim:

The ornamental design for a cover for tobacco pipes, as shown.

JACQUES SCHWALBE.
